179,750

PILOTING APPARATUS FOR USE IN GAUGING SURFACE FINISH

Fritz A. Zander, Ann Arbor, Mich., assignor to
Marion E. Abbott, Ann Arbor, Mich., trustee

Application December 29, 1955, Serial No. 39,757

Term of patent 14 years

(Cl. D52—1)

Fig. 1.

Fig. 2.

Figure 1 is a front perspective view of a piloting apparatus for use in gauging surface finish, showing my new design.

Figure 2 is a rear perspective view.

I claim:

The ornamental design for a piloting apparatus for use in gauging surface finish, substantially as shown.
